UNITED STATES PATENT OFFICE

FRANK DITCHFIELD, OF CLEVELAND, OHIO, ASSIGNOR TO THE YOUNGSTOWN STEEL DOOR COMPANY, OF CLEVELAND, OHIO, A CORPORATION OF OHIO

METAL CAR ROOF

Application filed January 9, 1929. Serial No. 331,373.

This invention relates to improvements in metal car roofs.

One object of my invention is to provide a durable thoroughly waterproofed flexible metal roof for cars which may be economically fabricated, applied and repaired.

Another object of my invention is to provide a metal car roof which is free from the usual ridges to the end that excessive collection of moisture, snow, sleet and the like and wind resistance, are minimized.

Another object is to provide a metal car roof which entirely avoids the use of any rivets through the roof sheets with consequent minimization of the tearing or corrodng of the sheets.

Another object of the invention is to provide a metal roof structure wherein the application or removal or replacement or inspection of the roof sheets may be effected with a minimum of labor, without the use of any special tools or equipment and without destructive effect on any element.

Another object of the invention is to so arrange the assembly of roof sheets, carlines and cap plates that such moisture as may enter any roof joint is automatically drained off from the interior without danger of the moisture dripping into the car on the lading.

Other objects of the invention are: To provide a complete weather seal around the entire roof; to allow for such flexibility in the roof sheets as conforms to good practice, and to provide simple and effective means for attaching the usual running boards without injury to the roof sheets.

Other objects of the invention will more clearly appear from the description and claims hereinafter following, taken in connection with the accompanying drawings.

In the drawings forming a part of this specification, Figure 1 is a broken top plan of a car showing my improved roof applied thereto. Figure 2 is an elevation of the end of the car roof. Figure 3 is a broken transverse sectional view upon an enlarged scale, corresponding to the line 3—3 of Figure 1. Figure 4 is a detail sectional view corresponding to the line 4—4 of Figure 3. Figure 5 is a detail sectional view corresponding to the

line 5—5 of Figure 3. Figure 6 is a longitudinal, part sectional view, part elevational view, the section corresponding to the ridge of the roof and one of the carlines being shown in elevation with the roof sheets removed from the ridge to the eaves. Figure 7 is a broken, end elevation of the car showing the roof structure. Figure 8 is an enlarged vertical sectional view, corresponding to the line 8—8 of Figure 7. Figure 9 is a part horizontal sectional view, part top plan, the section corresponding to the line 9—9 of Figure 7. And Figure 10 is a view similar to Figure 8, showing a modified form of construction at the end of the car.

In the particular embodiment of my improvements shown in Figures 1 to 9 of the drawings, 10 indicate the usual Z-bar side plates of the car, each having an upstanding flange 11, a horizontal web 12 and a depending outer flange 13, to which the metal side sheets 14 may be secured. At each end of the car, a pressed end plate is employed, also a Z-formation, the same having a depending outer flange 15, a horizontal web 16 and an upstanding vertical flange 17, the latter being tapered from the center to each side, to conform to the slope of the roof.

In carrying out my invention, I use specially formed carlines, each which is designated generally by the reference character A and the details of which are best illustrated in Figures 3, 4 and 6. As will be understood, the carlines A are spaced longitudinally of the roof the usual desired distance apart. Each carline is of generally channel cross section, having a lower horizontal web 18, upstanding side flanges 19—19 and top oppositely extended and horizontally disposed supporting longitudinal flanges 20—20. The web section 18 is given a gradual slope from the center line of the car roof to each side, as indicated best by the dotted line 118 in Figure 3. The depth of the side flanges 19 is gradually reduced from the center line of the car to each side, as also best shown in Figure 3, the change in width corresponding to the desired slope or pitch of the roof sheets. At each end, the carlines A are bent downwardly at right angles, as indicated at 21 Figure 3,

the lower edges of the downturned ends being disposed approximately midway the height of the side plate flange 11. An offset 22 is formed in each depending end 21 to accommodate the upwardly extending flange 23 of the horizontally disposed angle iron which is riveted to the outer face of the side plate flange 11, said angle iron having a horizontally disposed and outwardly extending continuous flange 24 for the purpose hereinafter described. As will be understood, each angle iron 23-24 extends the full length of the car side and the ends thereof abut the projected end portions 25 of the vertical flanges 26 of corresponding angle members riveted to the outer face of the upstanding flange 17 of the end plate, as best shown in Figures 8 and 9. Said angle member has also an outwardly extended horizontal flange 27 for the purpose hereinafter described. In this connection, it will be understood that the angle member 26-27 at each end of the car slopes in accordance with the pitch of the roof and, further, the upstanding flange 26 is preferably formed with an inturned narrow supporting flange 28 on which the adjacent roof sheet is supported, as shown in Figure 8.

Roof sheets, indicated generally by the reference character B, are employed, each of which is of a width corresponding to the distance between end plate and nearest carline or the distance between carlines. Each said roof sheet extends from car side to car side and is sloped upwardly to the center line of the car to provide the desired pitch for the roof and, along each edge, each sheet is formed with a downturned marginal flange 29, the flanges 29 of two adjacent sheets depending within the upwardly facing channel carline A, as best shown in Figure 4. In the case of the end roof sheets, those edges of the sheets at the extreme ends of the car are rounded over, as indicated at 30, and then extend vertically downward, as indicated at 31, so as to project below the horizontal flange 27 of the end angle member 26-27. Each end roof sheet is further rounded at the car corners, as indicated at 32 in Figure 9. At each end, each roof sheet B is rounded as indicated at 33 and thence terminates in an overhanging depending flange 34, the latter extending below the horizontal flange 24 of the corresponding side angle member 23-24, as shown in Figure 3.

The sheets B are made of sufficient width so that the depending side flanges 29 thereof will be inwardly spaced an appreciable distance, namely, from the side flanges 19 of the carlines, as shown in Figure 4, thus permitting a certain amount of shift of the sheets relative to the carlines, to take care of any weaving or distortion of the roof when the car is in service.

To weather-protect the joints of adjacent roof sheets B at each carline, I employ a cap

plate designated generally by the reference character C, said cap plate C being of generally T-cross section and having oppositely extended horizontally disposed flanges 35-35 and a depending centrally disposed web 36. The flanges 35 are made of such width that they not only overlap the adjacent portions of the roof sheets but also overlap, to an appreciable extent, the supporting flanges 20 of the carlines. The web 36, at the center line of the car, is of lesser depth than the depth of the channel carline A, as indicated by the dotted line 136 in Figure 3. Intermediate the center line and the sides of the car, the web 36 is chamfered as indicated by the dotted lines 236, so as to maintain a space between the lower edges 136-236 and the web section 18 of the carline and thus permit any moisture that may enter the joints and which comes on the depending web 36, to drip off into the channel carline and thus allow the moisture to drain down the sloping channel carline without danger of the moisture collecting and remaining in spots which might otherwise cause corrosion. In this connection, it will be noted that any moisture dripping into the channel carlines will readily flow off the ends thereof and drip down first onto the side angle member 23-24 and off of the latter at each carline. Each cap plate C is further bent at each side of the car, as indicated at 37, and the web 36 is further chamfered at each end on the depending section, as indicated at 336 in Figure 3. To secure the cap plates C in place and hence to maintain the roof sheets in place, the following means are employed. Preferably, at each side of the center of each carline and about at the middle, is utilized a tapered securing pin designated generally by the reference character D. The latter has a head 38, a tapered shank 39 and, intermediate its ends and on the portion of the shank within the channel carline, is formed with two annular grooves 40-40, for the purpose hereinafter specified. The pins D are extended horizontally through alined openings in the side flanges 19 of the carline and, when driven home, are secured in place by cotters 41 and washers 42 between the cotters and the adjacent carline, as clearly shown in Figure 4.

Referring to Figure 4, it will also be noted that the depending web 36 of the cap plate C is provided with an opening 43 to receive the shank of the pin D and, due to the tapered formation of the pin shank, the latter will act as a wedge in pulling the cap plate C tightly down into position. Where the securing pins D are located, the depending edge flanges 29 of the roof sheets B may be notched, as indicated at 44, to accommodate the pins, as will be obvious.

A generally similar arrangement is employed to fasten each of the downturned ends of the roof sheets. Referring to Figure 3, one of the securing pins is indicated at E, the

latter having its head at the outer end between which and the adjacent portion of the sheet is interposed a washer 45. In this instance, the pin is extended through the flange 23 of the angle member 23-24 and the upstanding flange 11 of the side plate and secured by cotter 46 with interposed washer 47. The pin E is also formed with an annular groove 48 beneath the sheet, for the purpose hereinafter described. By referring to Figures 8 and 9, it will be seen that similar attaching means are employed, for the overhanging flanges of the endmost roof sheets.

With the securing and attaching means described, it will be observed that the roof sheets are tightly clamped against the carlines and end plates of the car without any holes or perforations in the roof sheets and without the necessity of using any rivets. Further, the securing pins D and E may be readily applied or removed without the use of any special tools and very quickly, thus minimizing the cost of assembly or repairs or inspection. In the case of the pins D, the latter are obviously on the interior of the car below the roof sheets and thereby efficiently weather-protected. In the event any moisture enters through the joints of the roof sheets at the carlines or at the sides of the car in the case of the pins E, and such moisture collects on the securing pins, it is evident that the annular grooves 40 and 48 are so placed that such moisture cannot run the full length of the pin shanks but will collect in the grooves and drip from the sharp shoulders provided thereby; that is, the annular grooves 40 and 48 automatically serve to insure dripping of moisture from the pins before it can flow to the interior of the car or to the lading.

At the ends of the car, as shown in Figures 8 and 9, I preferably employ short sections of angles 49 where each pin E is used and through which the shanks of the latter are extended so as to prevent lifting of the end portions of the roof sheets, it being understood that said angle sections 49 are riveted to the end angle member 26-27.

Referring to the modification shown in Figure 10, the only difference over the construction illustrated in Figure 8 is that the end member 126 is specially formed with an extra depending section 50 and an outturned lower horizontal flange 51, a flange 127 being retained and the edge of which engages the downturned flange of the corresponding end sheet.

With the construction so far described, it will be observed that after the carlines are in place, the roof sheets may be very quickly and easily applied and the cap plates also applied and secured in position by inserting the pins D and E. Further, the structure at the joints is such as to eliminate the usual ridges, thus preventing the banking up of snow or sleet and also reducing the wind re-

sistance. Further, by referring to Figures 3 and 8, particularly, it will be seen that a very effective weather-sealed joint is provided entirely around the car roof where the depending flanges of the roof sheets bear against the outer edges of the outwardly extended flanges 24 and 27 of the side and end angle members, respectively, thus minimizing the possibility of rain or the like being driven up under the roof sheets when the car is in motion, while at the same time avoiding the necessity of riveting the sheets to the sides or ends of the car, as heretofore thought necessary.

Referring to Figures 1 and 2, it will be seen that the attaching brackets 52-52 for the usual running boards may be directly riveted or spot welded to the flanges 35 of the cap plates C and before the latter are placed in position. If rivets are employed to attach the brackets 52 to the cap plate C, the same may be so located as to bring the rivet holes inside of the roof sheet flanges 29 so that, should any moisture enter through these rivet holes, the same will drip into the channel carlines. In the case of the lateral running boards, the stiles thereof may be secured to the main running board as indicated at 53 and the lower or outer ends of said stiles as shown in Figure 2 may be riveted as indicated at 54 to a short section of channel iron 55 which in turn is riveted to the horizontal web of the side plate beyond the downturned flange of the roof sheet thus further avoiding any use of rivets passing through the roof sheets.

In the case of the end supporting brackets for the running board the latter will preferably be extended down to and riveted to the horizontal web section 16 of the end plate 17 although the details of this are not deemed necessary of illustration in the drawings.

Referring more particularly to Figure 3 of the drawings attention is called to the fact that an air pocket is formed by the angle flange 24 the portion of the roof sheet which depends therebelow the opposite portion of the side plate flange 11 and a portion of the web, 10, of the latter. Any rain snow or the like which may be driven beneath the edge of the roof sheet is caught in this pocket and its momentum destroyed so that, practically, none may pass the weather seal joint between the flange 24 and depending portion of the roof sheet. Any moisture which may succeed in passing this line of weather seal, will again be caught in a second pocket above the flange 24 and because of its momentum having been practically totally destroyed, it is substantially impossible for any moisture to pass up over the edge of the side plate flange 11. Similarly, a pocket effect is provided at the ends of the car as is shown in Figure 8, below the angle flange 27, and although this pocket is not quite as effective as that at the sides of the car, it is more than compensated for by the fact that a second line of weather seal is

provided between the roof sheets and the supporting flange 28. In the modification of Figure 10, an air pocket below the sealing flange is provided of substantially identical form as that shown in Figure 3.

5 I have herein shown and described what I now consider the preferred manner of carrying out the invention, but the same is merely illustrative and I contemplate all changes 10 and modifications as come within the scope of the claims appended hereto.

I claim:

15 1. In a metal car roof, the combination with side plates each having an upstanding flange; of a member extended lengthwise of each side plate flange and each having an outwardly projecting flange; carlines; roof sheets extending between carlines and having their ends overhanging and engaging said 20 outwardly extending flanges to form a weather seal therewith; and readily detachable means including devices extended through the sheets and side plates for retaining said sheets in position.

25 2. In a metal car roof, the combination with Z-side plates each having one flange thereof extending upwardly; of an angle member extending lengthwise of and secured to each upstanding flange, the angle member 30 having one of its flanges extended horizontally outward; carlines secured to said side plates; roof sheets extending between carlines and having their ends overhanging and engaging the outwardly extended flanges of 35 said angle irons to form a weather seal therewith; and means for retaining the sheets in place including detachable devices extended through the roof sheets and side plates.

40 3. In a metal car roof, the combination with Z-side plates each having one flange thereof extending upwardly; of an angle member extending lengthwise of and secured to each upstanding flange, the angle member having one of its flanges extended horizontally outward; carlines secured to said side plates; roof sheets extending between carlines and having their ends overhanging and engaging the outwardly extended flanges of 45 said angle irons to form a weather seal therewith; and means for retaining the sheets in place, said means including readily detachable pins extended through the sheets and side plates.

55 4. In a metal car roof having side plates, the combination with channel section carlines having the channel formations opening upwardly, the web sections of the carlines sloping downwardly from the center line of the car to each side, the ends of said carlines 60 being bent downwardly at the sides of the car and engaging over the side plates; roof sheets between carlines and extending continuously from side to side of the car, said roof sheets having edge flanges extended 65 within the carlines; T-section cap plates, one

at each carline and each having its web depending within the carline; and means for securing the cap plates to the carlines whereby any moisture entering the joints between cap plates and sheets will be automatically drained to the sides of the car by the carlines.

70 5. In a metal car roof, the combination with roof frame elements; of roof sheets; and means for retaining the sheets in place including securing pins extended through the frame elements beneath the roof, each of said pins being formed, intermediate its ends, with shoulders providing dripping edges for moisture whereby to prevent moisture flowing lengthwise of and to the ends of said pins.

75 6. As an article of manufacture, a securing pin for metal car roofs, said pin having a drip-forming annular groove intermediate the ends of its shank whereby to prevent flow of moisture to the ends of the pin.

80 7. In a metal car roof, the combination with an end plate; of a roof sheet extended beyond said end plate and provided with a downturned flange; extended below the top edge of the end plate; and means extending between said downturned flange and end plate providing a weather seal joint therebetween.

85 8. In a metal car roof, the combination with an end plate having an upstanding flange; of an angle member secured to the outer face of said flange, said angle member having an outwardly extended flange; and an end roof sheet extended beyond said end plate and provided with a depending flange engaging said outwardly extended flange of the angle member and providing therewith a weather seal.

90 9. In a metal car roof, the combination with an end plate; of a roof sheet extended beyond said end plate and provided with a downturned flange extended below the top edge of the end plate; means extending between said flange and end plate providing a weather seal joint therebetween; and detachable means securing said overhanging flange of the roof sheet to the end plate.

95 10. In a metal car roof, the combination with side and end plates; of angle members extending lengthwise of said plates on the outer faces thereof and each of said angle members having an outwardly extended flange; and roof sheets having flanges extending downwardly over and engaging said outwardly extending flanges of the angle members along the car side and ends of the car and forming therewith a weather seal, one angle member at each corner overlapping the end of the corresponding adjacent angle member and forming a seal therewith.

11. In a metal car roof, the combination with a Z-bar side plates, each having one flange thereof extending upwardly; of a plurality of carlines extending between side plates, each carline being of channel forma-

tion with the channel opening upwardly and provided with upper horizontally disposed supporting flanges, each carline, at its ends, being downwardly bent over and secured to the corresponding side plate; an angle bar extended lengthwise of and secured to the outer face of each upstanding flange of a side plate, each angle bar having an outwardly extending flange; roof sheets extending between carlines and from one side of the car to the other, each roof sheet having edge flanges depending within the corresponding carlines, each roof sheet also having its ends downturned and engaging with the corresponding outturned flanges of the angle bars; a cap plate of T-cross section associated with each carline, the flanges of the cap plates overlying adjacent portions of the roof sheets and the supporting flanges of the carline and the web thereof depending within the carline; and securing pins, each extended through alined openings in the side flanges of the carline and web of the cap plate, said pins being applied from the interior of the car.

12. In a metal car roof, the combination with carlines; of side and end plates; members secured to said plates and having outstanding flanges; and roof sheets having integral portions extended below said flanges along the sides and ends of the car and engageable with said flanges, said flanges and adjacent portions of the plates and the depending portions of the sheets forming an air pocket to destroy momentum of rain or the like and minimize danger of passage between said weather seal joint.

13. In a metal car roof, the combination with an end plate; of an end roof sheet having a flange extending down over and in spaced relation to the end plate; means interposed between the end plate and said sheet flange and forming therewith a weather seal; and means for keying said overhanging flange of the roof sheet to the end plate to prevent lifting of the sheet.

14. In a metal car roof, the combination with side plates, each side plate comprising a Z-bar with the web disposed horizontally and the inner flange extended upwardly; of a member secured to the upstanding flange of each Z-bar side plate, each member having a horizontally outwardly extended flange spaced above the web of the side plate; carlines extending from side plate to side plate; metal roof sheets, the roof sheets having outer flange portions extending downwardly past said horizontal flanges of said members and with the lower edges of said flanges closely adjacent the webs of the Z-bar side plates, said downturned flanges engaging said horizontal flanges whereby to provide a weatherseal therewith and an air pocket below the weatherseal; and means for securing said roof sheets in place.

15. In a metal car roof, the combination

with side plates, each provided with an outwardly extending horizontally disposed flange below the top edge thereof; of carlines, each carline being substantially of channel formation with the channel opening upwardly, the outer ends of said carlines being bent downwardly over the side plates and of similar cross section in the downturned portions; roof sheets extending transversely of the roof and having adjacent flanges bent downwardly and extending within the channel formation of the carlines; said roof sheets being also bent downwardly at their outer ends and in engagement with the downturned portions of the carlines, the downturned portions of the roof sheets engaging and forming an air seal with said outturned flanges of the side plates; cap plates overlying each pair of adjacent edges of the roof sheets and having downturned bent portions at their ends; and means for securing the cap plates in place.

In witness that I claim the foregoing I have hereunto subscribed my name this 17th day of December, 1928.

FRANK DITCHFIELD.
